UNITED STATES PATENT OFFICE.

THOMAS P. KILEY, OF NEW YORK, N. Y.

CLOSURE.

1,094,662.

Specification of Letters Patent. Patented Apr. 28, 1914.

Application filed August 4, 1913. Serial No. 782,865.

To all whom it may concern:

Be it known that I, THOMAS P. KILEY, a citizen of the United States, residing in the borough of the Bronx, city, county, and 5 State of New York, have invented a certain new and useful Improvement in Closures, of which the following is a specification.

The invention relates to improvements in closures and has for its objects to produce 10 a closure for tubs, barrels, and for other analogous purposes.

Before my invention, the method of securing the burlap or other material on the tub or other container was by nailing the 15 same to the top or side; said method is very inefficient, consumes considerable time to fasten the covering and destroys or lessens the life of the covering material and the tub or container, and also frequently results in injury to the workmen owing to 20 the fact that the workmen tear their fingers through the nailing, and this sometimes results in blood poisoning. With my invention the nailing of the cover is eliminated, 25 the cover is very quickly and securely fastened, the material is not injured, and the life of covering, tub or other container is materially lengthened; the possibility of injury to the workmen is removed; the covering 30 can be readily and easily removed or adjusted, and at the same time providing a closure which is securely locked.

These and further objects will more fully appear from an examination of the specification and accompanying drawings taken together or separately.

My invention is illustrated in the drawings in which the same parts are designated by similar reference characters in all the 40 figures.

Figure 1 is a perspective view of a portion of a tub equipped with my improved closure. Fig. 2 is a side elevation of the same on an enlarged scale. Fig. 3 is a plan view. Fig. 4 is a section with the covering removed. Fig. 5 is a sectional detail view.

In the embodiment illustrated, the apparatus comprises a tub or a like container 1. The tub is provided with a covering 2, 45 of burlap, canvas or of similar fabric.

3 represents a semicircular bow which is provided at each end with a depending ear 4. These ears carry pins 5 by means of 50 which the bow is pivoted to the tub. Washers 8 are placed over the pins 5 to properly

space the ears with respect to the body of the container. The bow 3 carries a pair of pins 7 disposed on a plane above that of the pins 5, and to these pins are pivoted the ends of a semicircular bow section 6. 60

One side of the tub is provided with a projection or stud 9, and the bow section 6 has a perforation 10 which engages the stud when the bow is in locking position. Diametrically opposite the perforation 10, the 65 bow 3 is provided with a similar aperture 11. Directly below the aperture 11 the tub is provided with a staple 12. A wire 13 may be passed through the aperture 11 and staple 12 and its ends embedded in a lead 70 or other seal 14 thereby effectually locking the covering in position, and therefore prevents tampering with the contents of the container.

The operation of my improved device is 75 as follows: The bows 3 and 6 are raised to the position shown in Fig. 4, and the covering 2 is placed over the top of the tub with its edges extending downward around the upper edge of the tub. The bow 6 is 80 then brought down until its perforation 10 is brought into alinement with the stud 9. The bow 3 is then rocked in its pivot and brought down around the other side of the tub drawing the bow 6 into close contact 85 with the tub and causing the stud 9 to enter the perforation 10. This will clamp the depending edge of the cover against the upper edge of the tub and the engagement of the stud and perforation will lock the bow 6 in position. When the bow 3 is in position 90 around the tub, the wire 13 is passed through the aperture 11 and the staple 12 and its ends are embedded in a lead or other seal in the usual manner, which prevents the 95 tampering with the contents of the container.

When the package is to be opened, the seal is broken, the bows swung upward to 100 the position shown in Fig. 4 when the covering may be pulled off. The covering is not injured and may be used over again.

In accordance with the provisions of the 105 patent statutes, I have described the principle of my invention together with the apparatus which I now consider to represent the best embodiment thereof, but I desire to have it understood that the apparatus shown is merely illustrative and that the invention 110 can be carried out in other ways.

Having now described my invention, what I claim as new and desire to secure by Letters Patent is:

1. The combination with a container and a covering therefor, of a bow pivoted to the container, means for locking the bow against movement, a second bow pivoted to the first bow and means for locking the last mentioned bow against movement.
2. The combination with a container and a covering therefor, of a bow pivoted to the container, means for locking the bow against movement, a second bow pivoted to the first bow and means for locking the last mentioned bow against movement, and means whereby the covering will be clamped between the bows and the container.
3. The combination with a container and a covering for the same, of a bow pivoted to the container, a second bow pivoted to the first bow, and means for locking the bows to the container.
4. The combination with a container and

a cover therefor, said cover being of greater diameter than the container, of a bow pivoted to the container, a second bow pivoted to the first bow and means whereby said bows will engage the projecting edge of the covering with the side of the container and lock it in position.

5. The combination with a container and a flexible covering for the same, of a bow pivoted to the container, a perforation in the bow, an eye secured to the container, a wire passing through the perforation, and the eye for locking the bow to the container, a second bow pivoted to the first bow, a perforation in the second bow and a stud on the container for engagement with the last named perforation.

This specification signed and witnessed this 24th day of July, 1913.

THOMAS P. KILEY.
